UNITED STATES PATENT OFFICE.

JAMES M. PULLEN, OF OZARK, MISSOURI.

TEMPERATURE-REGULATING APPARATUS.

939,858.

Specification of Letters Patent.

Patented Nov. 9, 1909.

Application filed January 25, 1908. Serial No. 474,130.

To all whom it may concern:

Be it known that I, JAMES M. PULLEN, a citizen of the United States, residing at Ozark, in the county of Christian and State 5 of Missouri, have invented certain new and useful Improvements in Temperature-Regulating Apparatus, of which the following is a specification, reference being had to the accompanying drawings.

10 This invention relates to improvements in temperature regulating apparatus and to one more particularly designed for use in photographic developing work.

The object of the invention is to provide a 15 simple and practical apparatus of this character which may be used to either lower or raise the temperature of chemicals in a developing tray and for analogous purposes.

With the above and other objects in view, 20 the invention consists of the novel features of construction and the combination and arrangement of parts hereinafter fully described and claimed, and illustrated in the accompanying drawings, in which—

25 Figure 1 is a perspective view of my improved apparatus showing it set up for heating a tray supporting table, the lamp or heater being omitted; Fig. 2 is a vertical section through the apparatus showing the lamp in position; Fig. 3 is a horizontal section through the tray supporting or work table shown in Fig. 1; Fig. 4 is a view similar to Fig. 1 showing the apparatus adapted for cooling or lowering the temperature of 30 developing trays or other objects placed on the table; and Fig. 5 is a vertical sectional view through the parts shown in Fig. 4.

Referring more particularly to the drawings, the numeral 1 denotes a supporting 40 frame or stand having an open top portion 2 in which is removably supported a body 3 of the temperature regulating apparatus or device. In the lower portion of the stand 2 is a support 4 for an oil lamp 5 or a similar 45 heater.

The body 3 is preferably in the form of a cylindrical drum and arranged within it is a smaller drum 6, the space between said drums forming a water chamber 7. The 50 closed ends 8, 9 of the drums 3, 6 are spaced apart and their opposite open ends are united by an annular bridge plate or ring 8^a. Formed in the side wall of the outer drum or body 3 are two threaded openings in which 55 are removably arranged the threaded ends of flow and return pipes 10, 11 adapted to

have their other ends connected to a device to be heated or cooled by the water in the space 7 circulating through said pipes.

When the device is to be used for heating 60 purposes it is arranged in the stand 1, as shown in Figs. 1 and 2, and the lamp 5 is placed in the bottom portion of said stand so as to project up into the inner drum 6, which latter forms a heating chamber; but 65 when the apparatus is to be used for cooling purposes the body is removed from the stand 3 and inverted, as shown in Figs. 4 and 5, the pipes 10, 11 being interchanged in the threaded openings of the body or drum 3. 70 When used as shown in Figs. 4 and 5, the inner drum 6 forms a receptacle for ice or other cooling mixture and its open top may be closed by a removable lid or cover 12. When used as shown in Figs. 1 and 2, the 75 heat and products of combustion from the lamp 5 escape through a centrally arranged pipe 13 which extends through the closed ends 8, 9 of the two drums 3, 6. Said pipe 13 is adapted to be closed by a removable 80 plug 14 when the body is inverted and used as a cooling device, as shown in Fig. 5. To permit water to be drained from the ice in the drum 6 a cock 15 is preferably screwed into a threaded opening in the pipe 13 and 85 this threaded opening may be closed by a screw plug 16 when the cock 15 is removed and when the body is used as a heating device, as shown in Fig. 2.

To permit the water space or chamber 7 90 to be filled with water or other liquid the end 8 of the outer drum is formed with a filling opening 17 adapted to be closed by a removable screw plug 18.

For the purpose of permitting water to be 95 drawn from the chamber 7 when the body or drum 3 is in either of its two positions in the supporting stand 1, pipes 19, 20 are screwed into the ring or plate 8^a and the end 8 and they are formed in their sides with 100 threaded openings adapted to receive either a draw off cock 21 or a plug 22. If desired, the outer ends of the pipes 19, 20 may be closed by screw plugs or caps 23. When the body is used as a heating device, as in Fig. 105 2, the cock 21 is arranged in the pipe 19 and when it is inverted, as shown in Fig. 5, said cock 21 is changed to the pipe 20.

24 denotes a work table or stand beneath the removable top plate 25 of which is arranged a coil of pipe 26. The projecting 110 ends 27, 28 of the coil contain controlling

valves 29, 30 and are detachably connected by unions 31, 32 to the pipes 10, 11.

In using the apparatus, when it is desired to heat or raise the temperature of chemicals in the photographic developing tray, the latter may be placed on the top 25 of the table or, when said top is removed, directly upon the coil 26 and the lamp 5 is lighted, the parts of the apparatus being arranged, as shown in Figs. 1 and 2. The heat of the lamp will heat the water in the chamber or space 7 and as the heated water rises it will pass through the pipe 10, then through the coil 26 and return through the pipe 11 to the body, which latter in such case serves as a boiler. In warm weather, when it is desired to cool or lower the temperature of developing chemicals or the like, cold water may be made to circulate through the coil 26 by moving the lamp 5 from the stand 1, inverting or reversing the position of the body 8 in said stand, as shown in Figs. 4 and 5, and placing ice or other temperature lowering material in the inner drum 6 and applying the cover 12 to the latter.

From the foregoing it will be seen that the invention provides an exceedingly simple and practical device of this character which may be used either for raising or lowering the temperature of developing chemicals and, while I have shown and described the invention as especially adapted for this use, it will be understood that the invention may be used in other ways and for other purposes.

Having thus described the invention what is claimed is:

1. In a temperature regulating apparatus, the combination of a stand having an open top and means in its bottom for supporting a heater, a body removably and reversibly arranged in the open top of the stand and consisting of outer and inner spaced drums united at one end by an annular ring and

each being provided with a closed end, said closed ends being spaced apart as well as the remainder of said drums in order to provide a liquid-containing chamber closed at both ends, a pipe extending through the closed ends of said drums, said pipe being adapted to be opened when the body is in one position and closed when in the reversed position, and flow and return pipes communicating with said chamber adjacent the opposite ends of the body. 55

2. In a temperature regulating apparatus, the combination of a body having outer and inner drums united at one end by an annular ring and having closed ends, said closed ends being spaced apart as well as the remainder of said drums in order to provide a liquid-containing chamber closed at both ends, a pipe extending through the closed ends of said drums, said pipe being adapted to be opened when the body is in one position and closed when in the reversed position, flow and return pipes in communication with said chamber at points adjacent the opposite ends of the body, pipes projecting from the opposite ends of the body and in communication with the space or chamber between the drums, the last mentioned pipes having their outer ends closed and their side portions formed with openings, a cock and a plug interchangeably arranged in the last mentioned openings, the closed end of the outer drum being formed with a filling opening, a removable closure for the latter, and means for supporting said body with either end uppermost, the last mentioned means being adapted to support a heater. 70

In testimony whereof I hereunto affix my signature in the presence of two witnesses.

JAMES M. PULLEN.
